UNITED STATES PATENT OFFICE.

LOUIS BALDACCINI, OF MOHAWK, NEW YORK.

COMBINED SHADE-SUPPORT AND CURTAIN-BRACKET.

1,173,915.

Specification of Letters Patent. Patented Feb. 29, 1916.

Application filed May 5, 1915. Serial No. 26,126.

To all whom it may concern:

Be it known that I, LOUIS BALDACCINI, a subject of Italy, residing at Mohawk, in the county of Herkimer and State of New York, 5 have invented new and useful Improvements in Combined Shade-Supports and Curtain-Brackets, of which the following is a specification.

The present invention relates to improvements in combined shade supports and curtain brackets, the object being to provide a device of this character which is of an extremely simple construction, cheap to manufacture and which will perform the purpose 10 for which it is intended with ease and with accuracy, and the invention resides in the construction, combination and arrangement of parts set forth in the following specification and falling within the scope of the 15 appended claim.

In the drawing: Figure 1 is a perspective view illustrating my improved bracket supporting a curtain pole and shade roller as well as a rod for a supplemental drapery, 20 Fig. 2 is a perspective view of one of the brackets, and Fig. 3 is a plan view of the blank from which the bracket is formed.

In constructing my improvement I employ a sheet of metal which is stamped, as illustrated in Fig. 3 of the drawing, to provide each of the said brackets with a side member 1, and an end member 2 which is bent at a right angle to the side and which preferably is provided with substantially V-shaped slits 3, the metal between the slits being bent outwardly to provide prongs 4, and the said prongs are adapted to be inserted in the facing of the window casing. One of the flat sides of one of the members is formed approximately centrally with a round opening 6 to receive a pivot or pintle of a shade roller, the second member is slotted vertically with respect to the position of the device upon the window casing providing 40 the same with a rectangular slot 7, the said slot receiving the rectangular member provided upon the spring end of the said shade roller. The upper edges of each of the sides are formed with downwardly curved portions 8, providing pockets or holding members for the curtain roller and the edges of said sides, from the said curved depressions 8 are extended upwardly, the said ends being preferably bent at a right angle with re-

spect to the sides 1, as indicated by the numerals 9, and each of these extending portions being provided with a threaded opening to receive an adjustable element, preferably in the nature of a screw 10 which is arranged to overlie the curtain pole and prevent the same from being accidentally removed from the circular depressions or pockets 8. Furthermore, the outer edges of the side members 1, provided with the extensions 10, are slotted or otherwise provided with upwardly extending tongues 11 which are spaced suitable distance from the extensions 9, the space between the members 9 and the tongues 11 being adapted to receive a small brace rod which has draped thereon an auxiliary or ornamental curtain. The tongues may be in the form of V-shaped members or pins, so that the auxiliary curtain may be draped thereon without the employment of the brace rod above referred to.

From the above description, taken in connection with the accompanying drawing, the simplicity of the device, as well as the advantages thereof will, it is thought, be perfectly apparent to those skilled in the art to which such invention appertains without further detailed description.

Having thus described the invention, what I claim is:

A bracket formed from a sheet of bendable material comprising a straight end plate, a side plate extending angularly and upwardly from the end plate, said side being provided with an opening and having its upper edge above the opening formed with a rounded depression, the end of the side, at the outer wall provided by the depression, being bent angularly in a line with the end plate and being arranged parallel to but above the said end plate, an upwardly projecting rounded tongue upon the last mentioned plate, and a longitudinally adjustable element associated with said flat member and disposed above the rounded depression in the side.

In testimony whereof I affix my signature in presence of two witnesses.

LOUIS BALDACCINI.
